UNITED STATES PATENT OFFICE.

CHARLES WILLIAMSON, OF CRAWFORDSVILLE, INDIANA, ASSIGNOR TO
GEORGE W. WILLIAMSON, SR., AND GEORGE W. WILLIAMSON, JR., BOTH
OF OTTAWA, KANSAS.

CORN-HARVESTER.

SPECIFICATION forming part of Letters Patent No. 325,190, dated August 25, 1885.

Application filed October 24, 1884. (No model.)

To all whom it may concern:

Be it known that I, CHARLES WILLIAMSON, a citizen of the United States, residing at Crawfordsville, in the county of Montgomery and State of Indiana, have invented 5 a new and useful Corn-Harvester, of which the following is a specification.

My invention relates to corn-harvesters; and the objects of my invention are to provide 10 a strong and simple machine which will gather the ears of corn from the stalks, tear off the husks from the ears, and collect the ears in a box, which can be emptied at the will of the operator. I attain these objects 15 by the mechanism illustrated in the accompanying drawings, in which—

Figure 1 is a front view of my corn-harvester; Fig. 2, a top view of the same; Fig. 3, a side view of the same; Fig. 4, a vertical 20 cross-section through the machine on lines xx on Figs. 2 and 3; Fig. 5, a longitudinal vertical section on lines yy on Figs 1, 2, and 4; Fig. 6, a longitudinal vertical section on lines zz on Figs. 1, 2, and 4.

Similar letters refer to similar parts throughout the several views.

A is an arched frame or axle, the two ends of which form the axle-spindles a' and a for the wheels W' and W , that support the machine.

On the spindle a is loosely mounted the compound sprocket and gear wheel B , said wheel being provided with sprockets on its outer rim and with an internal gear. Into 35 the cogs of said wheel B engages the pinion f , which is keyed to the end of the horizontal shaft F , to the other end of which is keyed the bevel gear-wheel f' . The shaft F operates in a bearing or sleeve, a^3 , which forms part of 40 or is rigidly bolted to the arch A . The vertical bevel gear-wheel f' operates the horizontal bevel gear-wheel h' and the vertical shaft H , to which said wheel h' is secured. The shaft H is supported by and revolves in a box- 45 ing formed in or firmly secured to the arch A . Keyed to the shaft H , above the arch A , is the circular saw or cutter h . At each side of the saw or cutter h from the arch A rise the standards a^2 and a^2 , which at their upper

ends form bearings for the horizontal shaft D . 50 To one end of said shaft D is firmly secured the sprocket-wheel C . The rasp disks $d d$ are keyed to the shaft D between the bearings a^2 and a^2 in such a manner that while they rotate with the shaft D they are permitted to 55 slide sidewise on the said shaft D . Wound around the shaft D , between the bearings a^2 and a^2 and the disks $d d$, and between the disks d and d , are the spiral springs $o o o$. These springs hold the rasp-disks $d d$ in place 60 on the shaft D , permitting them to move laterally on said shaft. The disks $d d$ are provided with protruding teeth on each surface; hence I call them "rasp-disks." Slipped onto the two rods $E E'$ are the rasp-plates $e e e$, 65 one being located in the center between the disks $d d$, and one off to each side at equal distances from said disks $d d$. These plates $e e e$ are separated by the spiral springs $m m$, wound around the rods E' and E . The plates 70 are provided on each surface with protruding teeth, the same as the disks $d d$. The brackets $a^4 a^4$, being firmly secured to the standards $a^2 a^2$, or to the arch A , form the supports for the rods E and E' . Rigidly fastened to the 75 arch A and in front of the same, extending down to near the ground, are the fingers $S S$. Pivoted to an extension of the spindle a , under the arch A , is the arm G , to the fore end of which is bolted the tongue T of the machine. The lever L , having its fulcrum-point 80 on the said arm G , and being connected with the arch A by a pitman-rod, P , is used to raise or lower the fingers $S S S$ from or to the ground. The seat V of the driver is braced 85 onto the tongue T .

By pulling the lever L toward the rear the rod P pushes the arch A back and down, lifting the ends of the fingers $S S S$ above the ground, the arch pivoting and turning on its 90 spindles a and a' in the hubs of the wheels W and W' .

The pawl N and the ratchet g form the means to secure the lever L , the arch A , and the fingers $S S S$ in any desired position. The 95 pawl N slides up and down alongside of the lever L and engages with the notches $g g$, which are worked in a semicircle on the upper

edge of the tongue and lever-support G, the pawl being pressed down into said notches *g* by a spring, *n*, fastened to the pawl on its lower end and pressing at its upper end against 5 a shoulder, *l*, which is secured to the lever L and forms a guide for the pawl N to pass through, a similar guide, *l'*, being placed near the lower end of the pawl N. This or any similar locking device for the lever L can be 10 used. Pivoted between and to the two brackets *a*⁵ *a'*⁵, that are secured to and extend back from the arch A, is the box I, into which the ears of corn are collected. To enable the operator to dump this box I and empty its 15 contents on any desired spot, the dumping device K *k* is used. K is a treadle or foot-lever pivoted to the tongue T. This treadle K is connected with the box I by a rod, *k*, the said rod *k* being pivoted to the foot-lever K and to the side of 20 the box I at such points that a downward pressure on the lever K will depress the fore end of the box I and dump its contents.

The machine operates as follows: When the corn-harvester is to be transported to the field, 25 the fingers S S are raised above the ground by the aid of the lever L and secured in position by the locking device N *g* *n* *l* *l'*.

The machine travels on the wheels W' and 30 W. Arrived in the field, the machine is brought into position with the fingers S S S facing toward the end of a row of cornstalks. The wheel W is connected with the gear and sprocket-wheel B by the slip-bolt *w*, or any other device by which the two wheels can be 35 locked together, so that the wheel W becomes the driving-wheel of the whole mechanism. The team is then started, the cornstalks are guided by the fingers S S S, the ears of corn are pulled up toward and between the rasp- 40 plates *e* *e* *e* and the disks *d* *d*, and are cut from the stalks by the rotating saw or cutter *h*, the rotating rasp-disks *d* *d*, taking hold of the ears, press the same against the stationary plates *e* *e* *e*, and, by forcing the ears backward 45 and brushing them against the plates *e* *e* *e*, strip away the husks. The ears drop then at the rear into the box I. With the driving-wheel W rotates the combined sprocket and gear wheel B. The sprockets of the wheel 50 B operate by a chain, R, the sprocket-wheel C and the horizontal shaft D, and with the shaft D rotate the husking-disks *d* *d*.

To prevent the clogging or twisting of the 55 husking wheels and plates, the said wheels and plates are mounted on their respective shafts and rods with springs between their hubs, so that they will give laterally.

The pinion *f* is driven by engagement with the internal gear of the wheel B. The shaft 60 F and the bevel gear-wheel *f'* rotate with the pinion *f*. The bevel gear-wheel *f'* engages with the bevel gear-wheel *h'* and operates the shaft H and the circular saw or cutter *h*.

Having thus described the construction and 65 operation of my corn-harvester, what I claim, and desire to secure by Letters Patent, is—

1. In a corn-harvester, the arched frame or

axle A, having the axle-spindles *a* and *a'*, the wheels W and W', operating on said spindles *a* and *a'*, the supports or brackets *a*² *a*² *a*⁴ *a*⁴, 70 forming part of or being rigidly secured to the arched frame A, and the fingers S S S, extending downward from the arch A, in combination with the sprocket-wheel B, revolving on the spindle *a*, the removable slip or lock bolt *w*, connecting the wheels W and B, the shaft D, supported by the standards *a*³ and *a*², the husking rasp-disks *d* *d*, revolving with the shaft D, the springs *o* *o* *o*, arranged, as specified, on said shaft D, the sprocket-wheel C, 80 firmly secured to the shaft D, the chain R, transmitting power from the wheel B to the wheel C and the shaft D, and the stationary rasp-plates *e* *e* *e*, mounted on the rods E E', and separated by the springs *m* *m* *m*, all arranged as described, and for the purpose specified. 85

2. In a corn-harvester, the arched frame or axle A, having the axle-spindles *a* and *a'*, the wheels W and W', operating on said spindles *a* and *a'*, the sleeve or bracket *a*³, forming part of or being rigidly secured to the arched frame A, and the fingers S S S, extending downward from the arch A, in combination with the wheel B, revolving on the spindle *a*, 90 and being provided with an internal gear, the bolt *w*, connecting the wheels W and B, the shaft F, revolving in the sleeve *a*³, the pinion *f*, keyed to the shaft F and operated by the cog-wheel B, the bevel-gears *f'* *h'*, transmitting motion from the shaft F to the shaft H, and the circular saw or cutter *h*, secured to and revolving with the shaft H, all constructed 100 and described, and for the purpose specified. 105

3. In a corn-harvester, the arched frame or axle A, constructed as described, and provided with the fingers S S S, the wheels W and W', and the supports and brackets *a*² *a*² *a*³ *a*⁴ *a*⁴, 110 forming part of or being rigidly secured to the arched frame A, in combination with the combined sprocket and gear wheel B, the shaft D, the sprocket-wheel C, the chain R, transmitting motion from the wheel B to the shaft D, the revolving rasp-disks *d* *d*, movable laterally on the shaft D, the rods E and E', the 115 stationary rasp-plates *e* *e* *e*, mounted and movable laterally on said rods E and E', the springs *o* *o* *m* *m*, arranged as described, the pinion *f*, shaft F, and gear-wheel *f'*, and the saw or cutter *h*, shaft H, and gear-wheel *h'*, 120 all arranged and constructed as described, and for the purpose specified. 125

4. In a corn-harvester, the arched frame or axle A, constructed and provided with brackets and supports, as described, the fingers S S S, and the wheels W and W', in combination with the revolving rasp-disks *d* *d*, the stationary rasp-plates *e* *e* *e*, the revolving cutter *h*, the driving mechanisms for the rasp-disks *d* *d*, and the cutter *h*, constructed, as described, 130 the arm G, pivoted to the arched frame A, and provided with the notches *g*, and the lever L, rod P, and pawl N, forming a device for raising and lowering the fingers S S S, all

arranged as described, and for the purpose specified.

5. In a corn harvester, the arched frame or axle A, the fingers S S S, the supports or brackets a^2 a^3 a^4 a^5 a^6 , and the wheels W and W', all constructed as described, in combination with the stationary rasp-plates e e e, the revolving rasp-disks d d, the springs m m o o, arranged as described, the driving mechanism B R C D, the cutter h, its operating mechanism B f F f' h' H, the lifting device L P N g G, the tongue T, the box I,

pivoted to the brackets a^5 a^6 , as described, and the dumping mechanism k K, all constructed as described, and for the purpose 15 specified.

In testimony whereof I have signed my name to this specification in the presence of two subscribing witnesses.

CHARLES WILLIAMSON.
